US0D1013716S

(12) **United States Design Patent** (10) **Patent No.:** **US D1,013,716 S**
(45) **Date of Patent:** **** Feb. 6, 2024**

(54) **DISPLAY SCREEN OR PORTION THEREOF
WITH A GRAPHICAL USER INTERFACE**

(71) Applicant: **Instasize, Inc.**, Sandy, UT (US)

(72) Inventors: **Hector Raul Lopez**, South Jordan, UT (US); **John William Fabela**, Sandy, UT (US)

(73) Assignee: **Instasize, Inc.**, Sandy, UT (US)

(**) Term: **15 Years**

(21) Appl. No.: **29/776,818**

(22) Filed: **Apr. 1, 2021**

(51) **LOC (14) Cl.** **14-04**

(52) **U.S. Cl.**

USPC **D14/486**

(58) **Field of Classification Search**

USPC D14/485-495

CPC G06F 3/048-04897

See application file for complete search history.

(57) **CLAIM**

The ornamental design for a display screen or portion thereof with a graphical user interface, as shown and described.

DESCRIPTION

The FIGURE is a front view of a display screen or portion thereof with a graphical user interface showing the new design.

Within the drawings, the outermost broken lines illustrate the display screen or portion thereof and form no part of the claimed design. The remaining broken lines illustrate portions of the graphical user interface and form no part of the claimed design.

1 Claim, 1 Drawing Sheet
